Primary Examiner — Antoine Duval Davis(74) *Attorney, Agent, or Firm* — GTC Law Group PC & Affiliates(57) **CLAIM**

The ornamental design for a simultaneous localization and mapping (SLAM) device, as shown.

DESCRIPTION

FIG. 1 is a rear perspective view of a first embodiment of our new design;

FIG. 2 is a front perspective view thereof;

FIG. 3 is a front elevation view thereof;

FIG. 4 is a rear elevation view thereof;

FIG. 5 is a right side elevation view thereof;

FIG. 6 is a top side elevation view thereof;

FIG. 7 is a bottom side elevation view thereof; and,

FIG. 8 is a rear perspective view thereof.

The broken lines in FIGS. 1-7 are for environmental purposes only and form no part of the claimed design.
